UNITED STATES PATENT OFFICE.

WILLIAM H. BANZETT, OF BERGENFIELD, NEW JERSEY, ASSIGNOR TO MERCANTILE CORPORATION, OF DAYTON, OHIO, A CORPORATION OF NEW YORK.

MACHINE FOR APPLYING PATCHES TO PRECUT-WINDOW ENVELOP-BLANKS.

1,297,988.

Specification of Letters Patent. Patented Mar. 25, 1919.

Application filed April 8, 1916. Serial No. 89,769.

To all whom it may concern:

Be it known that I, WILLIAM H. BANZETT, a citizen of the United States, residing at Bergenfield, in the county of Bergen and 5 State of New Jersey, have invented certain new and useful Improvements in Machines for Applying Patches to Precut-Window Envelop-Blanks, of which the following is a full, clear, and exact description.

10 This invention relates to an improved patch attaching device for window envelop blanks of the form shown, described and claimed in Patents Nos. 1,104,162, 1,123,659, and 1,118,466. In the prior machines the 15 rhomb-shaped blanks were presented to the rotary platen or blank bed in such a manner that their minor axes were tangential to the periphery of the rotary platen and in advancing through the machine the minor axis 20 was at all times substantially parallel to the direction of travel. Such a structure and mode of operation necessitated a widthwise applying of patches. Under certain conditions as, for example, when very large blanks 25 are used this mode of operation becomes unsatisfactory. The present machine provides for applying the rhomb in a lengthwise manner to the rotary platen or blank bed. The rhomb blank is presented to the rotary 30 platen with the major axis tangential to the periphery thereof and in its passage through the machine the major axis of the blank extends circumferentially about the rotary platen cylinder. In other words, the blank 35 advances through the machine with the major axis parallel to the direction of travel therethrough. In this way patches may be applied lengthwise over the window apertures, and the operation of supplying and 40 applying the patches is simplified. This invention also includes improvements in the patch feeding, gripping and securing devices, which will be pointed out in more detail in the accompanying specification.

45 In the drawings

Figure 1 is side view of the improved machine. Certain parts are shown in section to show the construction.

Fig. 2 is a detail view of the devices which 50 remove the blanks from the stack and transfer them to the platen cylinder.

Fig. 3 is a diagrammatic view of the blanks showing the various steps performed by the machine in attaching the patches.

55 In more detail in the drawings, 10 repre-

sents the stack of precut window envelop blanks of the shape shown at A in Fig. 3. These blanks are carried on sloping rails 11 and are maintained in position on the rails by end clips 12. In front of and near the 60 upper edge of the pile of blanks is a rotary platen cylinder or blank bed 13. Below the platen cylinder are oscillating take off bars 14. These bars 14 are rocked toward cylinder 13 by a follower 15, which coöperates 65 with a cam on the shaft carrying the cylinder 13. The bars 14 are restored to their position against the stack by a spring. I also provide a finger bar 60, which contacts with the stack of blanks and holds them in 70 position after the take off bars move away. This finger bar is operated by a cam and follower 61 in one direction and by a spring 62 in the opposite direction.

The bars 14 carry air suction tubes 17, 75 which are open at their ends in the faces of bars 14, which are toward the blanks. The air suction in the tubes is adapted to withdraw one blank at a time from the stack and to hold the blank to the take off bars 80 until it is removed therefrom by the grippers on the platen cylinder. The air suction is produced by a pump (not shown) and is controlled by an air valve 16, operated by a rod, which coöperates with a cam on the 85 shaft carrying the gummer 18. The gummer rotates in harmony with the platen cylinder 13, and consequently the air suction is controlled in harmony with the rotation of platen 13 and with the oscillation of take 90 off bars 14. A suitable spring 19 holds the bar which operates the valve 16 against its cam and operates the valve in one direction.

When the take off bar has moved a blank 95 against the platen cylinder, a cam operated gripper 20 engages the leading corner of the blank, and other cam operated grippers 21, at the proper time, engage the notches in the sides of the blank. These grippers are 100 shown diagrammatically in dotted lines in Fig. 2. The above mentioned grippers hold the blank to the cylinder in its forward rotation aided by spring pressed rolls 22. A second idler roll 23 also aids in maintaining 105 the blank in proper position on the cylinder.

The devices just described are adapted to apply the precut blanks one at a time to the rotary platen cylinder. The blanks are presented in such a manner that the major axis 110

of each blank, as it is presented, is tangential to the periphery of the cylinder and in its travel through the machine after it is gripped onto the cylinder the major axis of 5 each blank extends circumferentially around the cylinder and in a direction parallel to the direction of travel of the blank.

Gummer 18 takes gum from the gum box by the usual ductor rolls and applies the 10 gum to the blank on the blank bed about the margins of the window as shown at B in Fig. 3.

Patch devices.

15 The transparent patch paper is rolled up on a supply roll 24, which roll is tensioned by a gravity brake 25. The paper web 26 is fed between feeding rolls 27 and 28 which are geared together to rotate in 20 unison. These rolls are adapted to be given an intermittent forward rotation, by the following mechanism. A suitable cam on the shaft carrying patch bed 37 forces a follower 29 outwardly against the action of 25 spring 30 and rocks segment 31 in a counterclockwise direction. During this movement, a ratchet and pawl device 32 is restored, the pawl moving idly over the ratchet. At the proper time the spring 30 forces the follower 29 inward, rocking the segment 31 and by means of the pawl and ratchet device turns the feed rolls 27 and 28 to a sufficient extent to advance a length of patch paper. The patch paper advances between 35 fixed knife 34 and movable knife 35 and between guides 36, which guide the patch over the rotary patch bed 37. At the proper period in the cycle the movable knife 35 is forced downward by a cam on the shaft carrying 40 gummer 18 and a patch is severed from the web 26. The rotary patch bed 37 is carried on a shaft 38, which is geared to rotate in unison with platen cylinder 13. At one end of the patch bed there are a 45 number of holes 40, which connect with a duct 41, leading to a duct in the center of shaft 38. This duct in the shaft 38 is adapted to be opened and closed by a suitable air valve (not shown), which leads to 50 any air suction means, such as a pump. The timing of the air valve is such that it opens just as the holes 40 pass under the patch strip. The suction of the air grips the patch to the patch bed and maintains it 55 in position thereon until the end of the patch has been rolled into contact with the gummed surface on the blank, which is carried by platen cylinder 13. The air valve then closes to suction and opens to the atmosphere and the patch can then leave the 60 patch bed and follow the blank to which it is secured by the gum.

In order that the patch be properly timed in its application to the rotary patch bed so 65 that it will accurately register with the win-

dow in the blank, I provide additional mechanism which will now be described. A feed roll 42 is mounted on a bell crank, which crank is lifted by a cam on the rotary patch bed shaft. The feed roll is provided with 70 gear teeth meshing with teeth on the gear 43, shown by dotted circle. The feed roll is also cut away as shown at 44. The operation of these parts is as follows: The patch is fed into the cut away portion 44 of feed 75 roll 42. At the proper period the feed roll is lowered by the cam and the part of the feed roll which is not cut away comes into contact with the leading end of the rotary patch bed. The feed roll 42 and the patch bed 37 80 then act as feed rolls for the patch paper and draw it forward. At the same time the air suction is applied to hold the patch to the patch bed. After the patch has been secured to the patch bed the feed roll is 85 lifted by its cam and maintained in elevated position ready for the next operation. It will be understood that the above described devices prevent any "missing" of patches which might take place if air alone were 90 utilized to pick up the stationary patches and cause them to move forward in unison with the patch bed. At the same time the application of the patches to the blank on the blank bed is accurately timed insuring 95 proper registration over the windows in the blank.

I also provide a pivoted idler roller 46, which is adapted to hold the loose end of the patch down on patch bed 37 in its forward rotation.

Blank delivery devices.

Just as the grippers 20 and 21 pass the median line of platen cylinder 13 and the 105 rotary patch bed 37, they are released permitting the blank to pass between vertical guides 47, which lead the blank to blank delivery rolls 48. It will be understood that the platen roll is slotted in its periphery to 110 provide clearance for the left hand guide fingers as shown by the breaking away of the sectioned periphery in Fig. 1.

After the blanks pass the feed rolls they are delivered to a delivery chain 49, which 115 is provided with suitable grippers 50, cooperating with posts 51 carried by the chain. A fixed cam 52 opens the grippers to receive the blank between the post and the grippers and a second fixed cam 53 opens 120 the grippers when the blank is to be removed from the chain. To remove the blank from the chain, I provide a flapper bar 54 suitably oscillated as by the cam and spring device as shown, which is adapted to 125 displace the blank to the right and place it upon storage rails 55. It will be understood that both the flapper bar and the chain operate in harmony with each other and with the platen cylinder 13.

In the operation of the device, the platen roll 13 and the patch bed 37 firmly press the patch and the blank together with a rolling action and produce the completed patched blank shown at C in Fig. 3. By reason of the air suction, means for holding the patches to the rotary patch bed, gripper fingers for holding the patch can be eliminated. This is an advantage as the use of gripper fingers for this purpose tends to slightly mar the envelop blank.

It is to be understood that my invention is not limited to the precise details of construction shown and described, but that various modifications can be made as will readily occur to those skilled in the art. What I claim as my invention is more particularly defined in the appended claims.

I claim:

20 1. In a patch applying machine, in combination, a rotary platen; means for supplying pre-cut notched rhomb shaped window envelop blanks from a stack to said rotary platen, said means having provisions to supply the said blanks with the major axes thereof tangential to the periphery of the rotary platen; said rotary platen having means which is adapted to grip the leading corner of the blank and withdraw the same from the stack, and having supplementary means for thereafter gripping the blank adjacent the notches to secure the same to the rotary platen; means for gumming the said blanks about the borders of the pre-cut window; a rotary patch bed; means for advancing patch material to the said rotary patch bed; means for securing said patch material to the rotary patch bed, said patch extending longitudinally about the periphery of the patch bed; means for rotating the patch bed for rolling the patch upon the blank and securing the patch thereto by the gum thereon; and means for concurrently disengaging the patch from the rotary patch bed.

45 2. In a patch applying machine, in combination, a rotary platen cylinder, means for supplying pre-cut notched rhomb shaped window envelop blanks from a stack to said rotary platen cylinder, said means having provisions to present the blanks to the rotary platen cylinder with the major axes of the blanks tangential to the periphery thereof, whereby a blank will advance around the platen cylinder with its major axis extending circumferentially around the periphery of the cylinder; said rotary platen cylinder having means which is adapted to grip the leading corner of the blank and withdraw the same from the stack, and having supplementary means for thereafter gripping the blank adjacent the notches to secure the same to the rotary platen cylinder; means for gumming the aforesaid blanks about the borders of the pre-cut windows; and means

for applying patch material over the aforesaid windows, said material being secured by the gummed borders to the said blank.

3. In a patch attaching device, in combination with a rotary blank bed carrying pre-cut gummed window envelop blanks; a rotary patch bed having air suction means to engage the patches thereto and adapted to roll the patches into engagement with the blanks on the blank bed; means for advancing patch material to said patch bed, and a coöperating intermittently effective patch feed means comprising a pressure roll adjacent the rotary patch bed and adapted to roll the patch material on to said bed.

4. In a device of the class described, in combination; a rotary blank bed; a rotary patch bed having air suction means for securing patches thereto, said patch bed being adapted to roll the said patches into engagement with the blanks on said blank bed; means for supplying patch material to said patch bed, said means comprising patch material feeding rolls; a severing knife, an intermittently effective timing roll adapted to press the patches firmly to the rotary patch bed to permit them being engaged by air suction and to coöperate with the patch bed to give the patches their initial advancing movement.

5. In a device of the class described, in combination, a rotary blank bed; a rotary patch bed adapted to carry patches into engagement with gummed blanks on said blank bed; means for supplying patch material to said patch bed, said means comprising a feeding means adapted to advance a length of patch material from the supply roll; a severing knife for cutting the patch material into the proper lengths; a feeding roll adapted to be raised and lowered from and into contact with the patch material on said patch bed and to thereby firmly press the said patches into close contact with the patch bed, and to thereby coöperate with the said patch bed to give the patches their initial advancing movement.

6. In a patch attaching device, in combination with a rotary blank bed adapted to carry pre-cut window envelop blanks; means for gumming the said blanks; means for rolling patch material into engagement with the gummed blanks, said means comprising a rotary patch bed, said patch bed having air suction means for maintaining the patches in position thereon, said air suction means comprising an air port adapted to coöperate with the leading end of the patch, and a timing means adapted to press the leading end of the patch firmly down upon the air port whereby missing of patches is obviated and correct registry attained.

7. In a patch attaching device, in combination with a rotary blank bed adapted to carry pre-cut window envelop blanks; means

for gumming the said blanks; means for rolling patch material into engagement with the gummed blanks, said means comprising a rotary patch bed, said patch bed having 5 air suction means for maintaining the patches in position thereon, said air suction means comprising an air port adapted to hold the leading end of the patch, and means for advancing patch material to said 10 patch bed and for pressing the leading end of the patch firmly down upon the air port concurrently with the advancement thereof, whereby missing of patches is obviated and the patches are accurately registered on the 15 patch bed.

8. In a machine of the class described, a cylinder over which the envelop blank is passed, a rotative patch holding block co-

operating with the cylinder and provided with suction devices by which a patch is 20 held thereon, said block being adapted to roll the patch upon the blank carried by the cylinder upon the rotation of the blank, a guide for supporting a patch in position to be engaged by said suction devices, and 25 means for registering the patch relatively to the patch holder as it passes from the guide to said patch holding block.

In testimony whereof I hereunto affix my signature in the presence of two subscribing 30 witnesses.

WILLIAM H. BANZETT.
